W. B. HENKEL

LOCK FOR DEMOUNTABLE RIMS

Filed Dec. 9, 1920

Fig. 1.

UNITED STATES PATENT OFFICE.

WILLIAM B. HENKEL, OF BALTIMORE, MARYLAND.

LOCK FOR DEMOUNTABLE RIMS.

Application filed December 9, 1920. Serial No. 429,339.

To all whom it may concern:

Be it known that I, WILLIAM B. HENKEL, a citizen of the United States, residing in the city of Baltimore, in the State of Maryland, have invented certain new and useful Improvements in a Lock for Demountable Rims, of which the following is a specification.

This invention relates to locks for demountable wheel rims of the type shown and described in my co-pending application executed September 10, 1920 filed Feb. 19, 1921, Serial Number 446,386.

The object of the invention is to provide a simple and efficient locking device for securing the ends of a sectional rim locking member to avoid accidental separation of the sections of said member.

With these and other objects in view, the invention consists in certain novel features of construction as hereinafter shown and described, and specifically pointed out in the claims.

In the accompanying drawing:

Fig. 1 represents a side elevation of a portion of a wheel equipped with one form of this improved lock.

Fig. 2 is a transverse section thereof taken on the line 2—2 of Fig. 1.

Fig. 3 is a detail plan view.

Fig. 4 is a transverse section showing a slightly different form of lock,

Fig. 5 is a plan view of the form shown in Fig. 4; and,

Fig. 6 is a detail plan view.

In the embodiment illustrated the device constituting this invention is shown applied to a demountable wheel rim carried by a wheel felly R. The rim is composed of two superposed fixed and removable members 1 and 2 respectively held assembled by a sectional locking member 5, the opposed ends of two of the sections 6 and 7 thereof being secured by the lock or connector 10 constituting this invention. The member 1 is a felly band and is secured to the felly R and the member 2 is a tire casing rim and is mounted on, as well as being connected with, the band 1.

This lock 10 comprises a substantially T-shaped member the head 11 of which is composed of laterally spaced plates 12 and 13 connected at their outer edges by an integral web 10^a to adapt the member 10 to be slipped over the offset portion 4 of flange 3 of member 1.

In the form as shown in Figs. 1, 2 and 3 the offset flange portion 4 of member 1 has extending edgewise therethrough an aperture 15 which registers with an aperture 16 passing through the web 10^a connecting plates 12 and 13, said aperture being located in a cutout portion or recess 17 of said web. A bolt 18 extends through these registering apertures and has a nut 19 engaged therewith and housed in said depression 17 and when screwed down firmly clamps member 10 to the flange 4 of member 1 operating to hold said member 10 in locking position.

In Figs. 4 and 5 the flange 4 is also apertured edgewise as in the other figures and the web of the connecting plates 12 and 13 is slotted longitudinally as at 16^a to receive a T-shaped locking key 20, the head 21 of which is flattened and apertured to receive a tool for locking and unlocking it. The slot 16^a terminates in a recess 16^b in said web and a groove-like seat 16^c intersects slot 16^a to receive the key head 21 to hold the key in locked position. The shank 22 of the key extends below the offset flange 4 and has a plate spring 23 carried by its projecting portion the ends of which engage notches 24 in the lower face of the flanged portion 4. A coiled spring 25 on said shank 22 is engaged at one end with the shank and at its other end extends through spring 23 and the turning of the key operates to screw said spring through the spring 23 to vary its tension, and the two operate to hold the key head seated in groove 16^c to secure the lock 10 in operative position.

The preferred embodiment of the invention is disclosed in the drawings and set forth in the specification, but it will be understood that any modifications within the scope of the claimed invention may be made in the construction without departing from the principle of the invention or sacrificing any of its advantages.

What I claim is:

1. The combination with a demountable wheel rim having a sectional locking flange; of a lock for the sections of said flange comprising a double walled connector with an apertured web connecting one edge of the walls, said walls being disconnected at their other edge to slip over one edge and connect the sections of said locking flange, said connector fitting between the ends of said locking flange, said flanged ends and connector having interengaging elements, a projection

2
carried by said rim to extend through the aperture in said web, and means to lock said projection and hold said connector in operative position, said connector lying wholly 5 within the plane of the flange forming a smooth unbroken connection between the ends of the flange.

2. The combination with a demountable wheel rim having a sectional locking member; of a lock for the sections of said member comprising a double walled connector, 10 with an apertured web connecting one edge of the walls, said walls being disconnected at their outer edge to slip over and connect the sections of said locking member, and a 15 spring locking element for securing said connector to the rim.

3. The combination with a demountable wheel rim having a sectional locking member; of a lock for the sections of said member comprising a double walled connector, 20 with an apertured web connecting one edge of the walls, said walls being disconnected at their outer edge to slip over and connect the sections of said locking member, a spring 25 locking element for securing said connector to the rim comprising a T-shaped key extending through the aperture in said web and through said rim, and a spring to hold said key in operative position.

In testimony whereof, I affix my signature hereto.

WILLIAM B. HENKEL.
